UNITED STATES PATENT OFFICE.

JOSHUA V. JARRETT, OF VALLEY MILLS, TEXAS.

BED-BOTTOM SPRING.

SPECIFICATION forming part of Letters Patent No. 252,469, dated January 17, 1882.

Application filed December 8, 1881. (No model.)

To all whom it may concern:

Be it known that I, JOSHUA V. JARRETT, a citizen of the United States, residing at Valley Mills, in the county of Bosque and State of Texas, have invented certain new and useful Improvements in Bed-Bottom Springs, of which the following is a specification, reference being had therein to the accompanying drawings.

Figure 1 is a top plan view of my improved spring. Fig. 2 is a side elevation of the same; and Fig. 3 is a modification, showing the spiral coils running in opposite directions.

This invention has relation to bed-springs; and the novelty consists in the construction of the same, as will be hereinafter more fully described, and particularly pointed out in the claim.

In the accompanying drawings similar letters of reference indicate like parts of the invention.

A A' are twin spirals, joined at their tops by the gridiron-shaped connection B, which is made of a series of parallels, b, so as to form a platform for the mattress to rest upon.

By this construction, in addition to the support furnished by the top spirals, the platform furnishes a broad level bearing for the mattress and prevents sagging between the springs or injury to the mattress itself. Also, the parallels b, being springs in themselves, additional comfort and elasticity are added to the bed, and the springs themselves are more readily adapted to the varying width of the slats of different beds.

Having thus fully described my invention, what I claim as new and useful, and desire to secure by Letters Patent, is—

As a new article of manufacture, a twin bed-spring formed in one piece, of the spirals A A' and platform B, made of a series of parallels, b, constructed substantially as and for the purpose set forth.

In testimony whereof I affix my signature in presence of two witnesses.

JOSHUA V. JARRETT.
